UNITED STATES PATENT OFFICE.

EARL J. BRACKEN, OF BUTTE, MONTANA.

TAG FASTENER.

Application filed August 28, 1923. Serial No. 659,824.

To all whom it may concern:

Be it known that I, EARL J. BRACKEN, a citizen of the United States, residing at Butte, in the county of Silver Bow, State of Montana, have invented certain new and useful Improvements in Tag Fasteners; and I do hereby declare the following to be a full, clear, and exact description of the invention, such as will enable others skilled 10 in the art to which it appertains to make and use the same.

This invention relates to new and useful improvements in fasteners and more particularly to that type of fasteners arranged 15 for attaching shipping tags and the like to the cord or wire with which a bundle, parcel or the like may be tied.

One object of the invention is to provide a novel and improved means for securing 20 a tag to a parcel or package without the use of cord.

Another object of the invention is to provide improved means for attaching the fastener to the parcel or package so that all 25 danger of it becoming disengaged therefrom is obviated.

A further object of the invention is to provide a fastener wherein the tag will, at 30 all times, be held separated from the attaching means and wherein the tag instead of being rigidly held, will be permitted to swing or hang freely at all times.

Other objects and advantages will become more apparent from the following description when taken in connection with the 35 accompanying drawing.

In the drawing:

Figure 1 shows, in elevation, one form of fastener which may be used for accomplishing the objects of the present invention.

Figures 2 and 3 are similar views of two other forms of fasteners which may be used for carrying the invention into practice.

Referring now to the drawing and more particularly to the form of the invention shown in Figure 1, there is disclosed a structure including a pair of substantially parallel arms 10 and 11, which are connected by the bight portion 12. The arm 11 is somewhat longer than the arm 10 and is bent upon itself to form the tag retaining eye 13. The free end portion of the arm 11 extends diagonally upward as shown at 14 and crosses the arm 10 as shown at 15, with 50 its end extended slightly therebeyond.

The free end portion of the arm 10 is bent

upwardly and pinched as shown at 16, from which point it extends upwardly and outwardly to form the arm 17 which terminates in a tongue 18, which tongue bears against the arm 11. It will be clearly seen that the arm 14 not only extends beyond the arm 11 but also projects slightly beyond the arm 17, so that there is provided what might be termed a double resistance. In other words, when the cord or wire is inserted between the arms 10 and 11 and the entire device is then pulled downwardly, the cord or wire must not only force the arm 14 outwardly but must also force the tongue 18 toward the arm 10, with the result that when the cord or wire is once engaged within the bight portion 12, there will be no danger of it becoming disengaged therefrom as it would be practically impossible for it to 60 pass the arm 14 and the tongue 18.

The form shown in Figure 2 includes an arm 20, which has its lower end portion bent upon itself to form the tag retaining eye 21, this end of the arm terminating in a hook 22 which engages the lower portion of the arm 20. The upper end portion of the arm 20 is also bent upon itself in the opposite direction to the lower portion, to form the downwardly and outwardly projecting short arm 23, which is bent upon itself to form the upwardly extending arm 24. This arm is pinched as shown at 25 and from this point it extends outwardly and upwardly to form the tongue 26, which 70 bears against the arm 20.

The form shown in Figure 3 comprises an arm 27, which has its upper end portion bent first downwardly and outwardly as shown at 28 and then downwardly and 75 slightly inwardly toward the arm 27, as shown at 29. The lower end portion is bent upon itself to form the eye 30 which is held clinched to the tag 31 by means of the clinched eyelet 32. The free end of the lower portion of the arm 27 is looped around the said arm as shown at 33, and the free end extends then upwardly and outwardly to form the tongue 34. The end of this tongue overlaps the downwardly and inwardly projecting portion 29, while the extremity of the said portion 29 extends beyond the tongue 34 and is spaced away therefrom as shown at 35.

By the use of these fasteners, tags may 110 be more readily and quickly attached to parcels, packages and the like. In form 1,

the tag eyelet is slipped onto the portion 14 and past the arm 11 into the eye 13. In Figure 2, the tag is engaged within the eye 21 by releasing the hook 22 from the arm 5 20 and then slipping the eyelet of the tag over the said hook.

What is claimed is:

1. A tag fastener including an arm bent in opposite directions to form a fastening 10 eye and a tag retaining eye, the tag retaining eye being formed with an extended portion which terminates within the fastening eye and provides a barrier between the eyes.
2. A tag fastener including an arm bent 15 to form a fastening eye and a tag retaining eye, the fastening eye being formed with a tongue, and the tag retaining eye being formed with an extended portion which projects past the arm and the tongue and provides a barrier between the eyes.
3. A tag fastener including an arm having 20 its lower end portion bent to form a tag retaining eye, the upper end portion of said arm being bent in the opposite direction to form a downwardly projecting arm which arm is bent upon itself to form a tongue which engages with the inner face of the first mentioned arm, the tag retaining eye being provided with an extended portion

which engages with the first mentioned arm 30 and tongue.

4. A tag fastener including an arm having its ends bent to form a fastening eye and a tag retaining eye, the fastening eye being formed with a tongue which contacts 35 with the arm, and the tag retaining eye being provided with an extended portion which contacts with the said arm and tongue and terminates within the fastening eye.

5. A tag fastener including an arm having its ends bent in opposite directions to form a fastening eye and a tag retaining eye, the said fastening eye comprising a downwardly projecting arm and an upwardly and inwardly extending tongue which contacts 40 with the said first arm, and the tag retaining eye being formed with an upwardly and diagonally extending portion which crosses the said first arm and tongue and contacts therewith and terminates within the fastening eye.

In testimony whereof, I affix my signature, in the presence of two witnesses.

EARL J. BRACKEN.
